(57) **CLAIM**

The ornamental design for a handle as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a handle according to our new design;

FIG. 2 is a bottom plan view thereof;

FIG. 3 is a left-side view elevation thereof;

FIG. 4 is a right-side view thereof;

FIG. 5 is a rear elevation view thereof;

FIG. 6 is a front elevation view thereof;

FIG. 7 is a top plan elevation view thereof;

FIG. 8 is a left-side perspective view thereof; and,

FIG. 9 is a rear and side perspective view thereof.
